UNITED STATES PATENT OFFICE.

JOHN L. DINSMOOR, OF NEW YORK, N. Y.

SEALABLE PACKAGE TIE.

Application filed September 18, 1924. Serial No. 738,342.

To all whom it may concern:

Be it known that I, JOHN L. DINSMOOR, a citizen of the United States, and a resident of New York, borough of Manhattan, in the county of New York and State of New York, have invented certain new and useful Improvements in Sealable Package Ties, of which the following is a specification.

This invention relates to sealable package ties and has for its object to provide a device of the class described, simple in construction, easily applied and adapted to be sealed by any one of a number of known seals. Other objects will appear later herein.

My improvements comprise features illustrated in their preferred embodiment in the drawing accompanying this specification, wherein:

Figure 1 is an annulet of fibrous material such as linen or cotton. Fig. 2 is a similar annulet of wire. Fig. 3 shows the annulet of Fig. 2 with a closed loop or eye formed from a portion thereof. Fig. 4 is similar to that of Fig. 3 and showing the eye laid close to another portion of the tie. Fig. 5 shows the annulet of Figs. 3 and 4 about the neck of a bag and the seal applied thereto. Fig. 6 shows the annulet of Fig. 2 provided with two opposite eyes. Fig. 7 shows the tie of Fig. 6 with its two eyes folded toward each other ready to receive a seal. Fig. 8 shows the annulet of Fig. 2 with two eyes formed therefrom, said eyes being formed nearer together than those of Fig. 6. Fig. 9 is similar to the showing of Fig. 8 but with the eyes still nearer together and having a flat metallic strip threaded through said eyes for sealing.

Ties of wire having eyes formed therein are known in the art as are also annulets adapted to be drawn taut about an article by twisting a bight of the material of which they are formed, but sealable package ties as set forth herein are believed to be new and to be a marked advance in the art.

Preferably my improved tie comprises a continuous annulet A, which, if formed of cord or the like as in Fig. 1, may be closed by sealing together the ends as at 2 by sealing wax or the like. If the annulet A is formed of metal, as in Fig. 2, the ends may be joined as at 3 by welding, brazing or the like. Eye 4 of Fig. 3 may be formed by twisting a bight of said annulet as at 5. In

Fig. 4 said eye 4 is folded down against the body of the tie, and in Fig. 5 the tie is shown applied to the neck of a bag B and a wire or cord 6 passed through said eye and about the contiguous portion of the tie. Said wire 6 may be sealed by the application thereto of the usual lead seal 7.

In the modification of Fig. 6, two eyes 4 and 8, oppositely disposed, are provided. In Fig. 7 said eyes are folded toward each other ready for the reception of a sealing member for locking them together. In the modification of Fig. 8, eyes 4 and 8 are formed from portions of the annulet nearer together than in Figs. 6 and 7. In Fig. 9 the eyes 4 and 8 are still nearer together and are locked to one another by means of a flat sealing strip of metal 9. In this modification, and in others, if desired, said eyes 4 and 8 are oblong in form to permit the free passage of flat strip 9.

There is thus provided a simple and efficient sealable package tie, easily applied and highly secure and effective in operation.

The term sealable tie, as herein used, will be understood to mean a tie having at least one closed loop or eye through which a sealing strip may be passed for locking by enclosure with another portion of said tie.

The term package as herein used will be understood to include a box, bale, bag or other article or container adapted to be encircled and sealed.

I claim:

1. A sealable package tie including in combination a flexible annulet adapted for encircling a package, an eye formed therein by twisting a bight thereof, said annulet being adapted for being drawn taut about the package by said twisting, and means passing through said eye and about a single portion of said annulet for sealing the tie.

2. A sealable package tie including in combination a flexible annulet adapted for encircling a package, two eyes formed therein by twisting bights thereof respectively, said annulet being adapted for being drawn taut about the package by said twisting, and means passing through said eyes for sealing said tie.

3. A sealable package tie including in combination a flexible annulet adapted for encircling a package, an oblong eye formed therein by twisting a bight thereof, and

means comprising a flat metallic strip passing through said eye and about a single portion of said annulet for sealing the tie.

4. A sealable package tie including in combination a flexible annulet adapted for encircling a package, two oblong eyes formed therein by twisting bights thereof respectively, said annulet being adapted for

being drawn taut about the package by said twisting, and means comprising a flat metallic strip passing through said eyes for sealing said tie. ¹⁰

In witness whereof, I hereby affix my signature this 17 day of September, 1924.

JOHN L. DINSMOOR.
